Primary Examiner — Richard E Chilcot*(74) Attorney, Agent, or Firm* — The Weintraub Group, P.L.C.**CLAIM**

The ornamental design for a carton, as shown and described.

DESCRIPTION

FIG. 1 is a front view of a first embodiment of a carton showing my new design;

FIG. 2 is a perspective view of the carton hereof;

FIG. 3 is a front view of the carton hereof;

FIG. 4 is a side view of the carton hereof; and,

FIG. 5 is a perspective view of the carton hereof as seen from a side opposite that of FIG. 2.

The broken lines shown in the views are for illustrative purposes only and form no part of the claimed design.
